Samuel W. Gibbs, of Albany, N. Y.
Assignee to John J. Rathbone, of same place
Letters Patent No. 39, dated May 7, 1861.
Whole No. 1404.

The schedule referred in these Letters Patent and making parts of the same.

Be it known that I, Samuel W. Gibbs, of the City of Albany, State of New York, have produced a new and original ornamental design for the plates of a parlor or hall stove, (Known as the Bouave Stove) and I declare the accompanying drawings forming part of this specification to be an accurate representation of the said plates of the stove with their ornaments; and that what I claim as my production and desire to secure by Letters Patent, is the combination and arrangement of figures and forms represented in the said drawings, forming together the ornamental design for the plates of a parlor or Hall Stove.
